CHARLES DYER, OF COAL RUN, OHIO.

Letters Patent No. 83,478, dated October 27, 1868.

IMPROVEMENT IN COMBINED CORN-PLANTER AND CULTIVATOR.

The Schedule referred to in these Letters Patent and making part of the same.

To all whom it may concern:

Be it known that I, CHARLES DYER, of Coal Run, in the county of Washington, and State of Ohio, have invented a new and improved Corn-Planter and Cultivator; and I do hereby declare that the following is a full, clear, and exact description thereof, which will enable others skilled in the art to make and use the same, reference being had to the accompanying drawings, forming a part of this specification.

This invention relates to a new and improved corn-planter and cultivator, and it consists in a new and improved construction of parts, as hereinafter fully shown and described, whereby a very desirable machine for the purpose specified is obtained.

In the accompanying sheet of drawings—

Figure 1 is a side sectional view of my invention.

Figure 2, a plan sectional view of a portion of the same.

Similar letters of reference indicate corresponding parts.

A represents an axle, having a wheel, B, on each end of it, and C is a rectangular frame, attached to the axle.

On this frame C the driver's seat D is secured, and in front of said seat a seed-box, E, is secured upon the frame, the former extending the whole width of the latter.

In the bottom of the seed-box there is fitted, longitudinally, a reciprocating bar, F, having holes *a* made through it, by means of which seed is discharged from the seed-box into flexible tubes G, which conduct the seed into rigid tubes H, which are attached to standards I, having furrow-opening shares J secured to their lower ends.

The holes *a* in the bar F may have thimbles fitted in them for the purpose of increasing or diminishing their capacity, according to the amount of seed to be

discharged at each dropping, and the bar F is operated by the driver or an attendant, through the media of a lever, K, connected by a rod, b, with a bent lever, L, attached to the under side of the seed-box. (See, more particularly, fig. 2.)

The standards I are braced by rods J $\times$, the front ends of which are connected, by joints *c*, to the front cross-piece of the frame C, and the rear ends connected, by joints *d*, to the standards.

The two standards are connected by a rod, *e*, which is connected, by links *f*, with cranks *g*, on a shaft, *h*, having a lever, K $\times$, at one end of it. By drawing back the lever K $\times$, the furrow-openers may be raised out of the ground, when necessary.

To the lower part of the standards, seed-coverers L $\times$ are attached.

In using the device as a cultivator, shares M, attached to standards N, which are secured to rods O, having their front ends connected by joints to the front cross-piece of the frame C, are used. A greater or less number of these shares may be employed, as desired.

The machine is extremely simple and efficient, may be constructed at a very moderate cost, and manipulated with the greatest facility.

Having thus described my invention,

I claim as new, and desire to secure by Letters Patent—

The described arrangement of the flexible tubes G, rigid tubes H, standards I, furrow-shares J, seed-coverers L $\times$, pivoted braces J $\times$, standard N, shares M, pivoted brace O, connecting-rod *f*, crank-shaft *g*, and lever K $\times$, as herein set forth for the purpose specified.

CHARLES DYER
